UNITED STATES PATENT OFFICE

127,720

DESIGN FOR A SPOON

Will A. Foster, Scarsdale, N. Y., assignor to The Borden Company, New York, N. Y., a corporation of New Jersey

Application March 20, 1941, Serial No. 99,742

Term of patent 14 years

To all whom it may concern:

Be it known that I, Will A. Foster, a citizen of the United States, residing at Scarsdale, in the county of Westchester and State of New York, have invented a new, original, and ornamental Design for Spoons, of which the following is a specification, reference being had to the accompanying drawing, forming a part thereof.

In the drawing,

embodying my new design.

blade of said spoon, along the line 3—3 of Figure 1.

I claim:

The ornamental design for a spoon, as shown.

WILL A. FOSTER.
